Garrettson Smith and Henry Brown, of Philadelphia, Pa.

Assignors to

Hayward Bartlett & Co. of Baltimore Md.

Letters Patent No. 1093. Dated April 12, 1859.

Ante-dated 29th March 1859.

The schedule referred to in these Letters Patent and making part of the same.

*****

To all whom it may concern:

Be it known, that we Garrettson Smith & Henry Brown, of the City and County of Philadelphia and State of Pennsylvania, have produced a new and original stone design designated the

Mount Vernon Airtight.

And we do hereby declare that the following is a full, clear and exact description of the same; reference being had to the annexed drawing, forming part of this Specification.

The side plate bears three raised panels A, B, C, the upper edge of the former having the form shown in the drawing and in addition to the moulding having the ornament a.

The panel A is ornamented in bas. relief with sweeping foliage b. entwined with branch c bearing fruit, the design and configuration being as shown in the drawing.

Panel B bears sweeping foliage in bas. relief and panel C an ornament of a similar character the design being as shown in the drawing.

At the lower corners and rear edge of the side plate are ornaments in bas. relief representing foliage. Above panel A. is the inscription "Patented 1859" and below this panel the words "Mount Vernon Airtight" in raised capitals and numerals.

The several portions of the design of this side plate are as set forth in the drawing.

The back plate P. bears an ornament in bas. relief composed of entwined foliage configuration as shown in the drawing.

The upper front plate D. bears the ornaments e, f, g, h, in bas. relief having the configuration shown in the drawing. And the front doors

2

Des. 1093 $\frac{1}{2}$

bear each an ornament made up of foliage and fruit having the design set forth in the drawing.

The foot F. is ornamented in bas-relief as set forth in the drawing.

We claim the design, configuration and arrangement of the several ornaments in bas-relief as above set forth and shown in the annexed drawing as a new stove design.
